UNITED STATES PATENT OFFICE.

JOSEPH J. TREMBLE, OF WHITEWOOD, SOUTH DAKOTA.

DESIGN FOR A LACING-HOOK.

SPECIFICATION forming part of Design No. 29,919, dated January 3, 1899.

Application filed December 1, 1898. Serial No. 698,009. Term of patent 14 years.

To all whom it may concern:

Be it known that I, JOSEPH J. TREMBLE, a citizen of the United States, residing at Whitewood, in the county of Lawrence, State of South Dakota, have invented and produced a new and original Design for a Lacing-Hook, of which the following is a specification, reference being had therein to the accompanying drawings.

10 In the accompanying drawings, Figure 1 represents a perspective of my design for a lacing-hook. Fig. 2 is a plan view, and Fig. 3 is a vertical cross-section.

As shown in the drawings, the leading or 15 material feature of my design consists of the unitary design substantially as shown in the accompanying drawings.

The head is formed with a concave outline

A and a convex outline A'; the same being extended to form an elongated crescent, the 20 said curved outline A' being merged into a base having rectangular outlines B. From the side lines B projections extend having angular outlines C.

Having described my invention, what I 25 claim as new, and desire to secure by Letters Patent, is—

The design for a lacing-hook as herein shown and described.

In testimony whereof I affix my signature 30 in presence of two witnesses.

JOSEPH J. TREMBLE.

Witnesses:

ALICE T. VAUGHAN,
R. R. DUNN.
